UNITED STATES PATENT OFFICE.

DAVID BRAINERD RAY, OF HUNTINGTON, NEW YORK.

SPACE FOR JUSTIFYING LINES OF TYPE.

No. 813,912.

Specification of Letters Patent.

Patented Feb. 27, 1906.

Application filed April 26, 1904. Serial No. 204,916.

To all whom it may concern.

Be it known that I, DAVID BRAINERD RAY, a citizen of the United States, residing in Huntington, Long Island, State of New York, have invented a new and useful Improvement in Spaces for Justifying Lines of Type, of which the following is a full and complete description.

My spaces are made of compressible non-elastic material and are placed between the words as the line is set up. When enough words are set up to form a line, it is shortened to the required length by pressure applied at the end thereof by any suitable means, whereby all the spaces are reduced in size. After the spaces have been used they can be restored to their original shape and used again.

Referring to the accompanying drawings, Figure 1 shows a line of type with spaces inserted ready for compression. Fig. 2 shows a line after compression. Fig. 3 shows a space ready for use. Fig. 4 shows a space reduced in size by compression, and Fig. 5 shows a perspective view of the space.

My space consists of a main stem A a little shorter than the type, but of the same width. The parts B B are bent back along the main stem. They may or may not be bent back far enough to touch the main stem A or they may be arched. When compressed, each end of the parts B B will move toward the middle of the stem A and in opposite directions, so that the space is not elongated by compression. This avoids lifting the type off their feet when the line is compressed.

The object of my invention is to form a simple and cheap space which can be easily compressed, so that lines of type can be justified or made of even length by end pressure by means of suitable mechanism all at once, thereby saving time, and can be easily restored after having been used, and also will brace the words apart firmly and evenly and will retain its proper width as a space after the compressing force has been removed. To accomplish this, I form my space of a single uncut strip of very thin metal of the width of a type of the font with which it is to be used. The middle of the strip is flat and forms the main stem or body A, and the ends B B are bent over along or on the body A. (See Fig. 3.) The ends B B are not forced down tightly on the body A. Preferably the

parts B B are curved or arched, one end 55 of the arch being movable along the main stem or body A when the space is flattened. By constructing the parts B B in the form of an arch I can secure sufficient strength and yet use very thin metal, so that the 60 space may be flattened when required to the thinnest dimensions. The parts B B extend outwardly from the main stem A an equal distance, thereby bracing the type apart 65 equally at top and bottom, and being of equal length yield equally under pressure. One end of the arched part B B is movable. The advantage of this novel form is that the 70 movable end of the arch resting on the main body A affords a strong and equal brace and yet will move along the main stem or body A when the space is flattened toward the middle thereof, so that the space will not be elongated by compression, and thereby avoids lifting the type off their feet.

While I do not limit myself to the arched shape of the parts B B as shown in the drawings, yet I consider that shape preferable because it braces the words apart evenly and firmly and it can be compressed without injuring the soft metal of which the type is composed.

I do not limit myself to the use of non-resilient material in the construction of the space, but I prefer to use non-resilient material because resilient spaces require powerful mechanism for their compression and they have a tendency to spring the line of type upward or to scatter the type in all directions when the pressure is released or a word is removed in "correcting proof."

My space is novel, simple, and easily put into practical use and is adapted to setting type by hand or by a machine.

What I claim is—

1. A compressible space consisting of a main part or stem having its ends bent back along said main stem once only, whereby the space when compressed equals only two thicknesses of the material of which the space is made.
2. A compressible space consisting of a main part or stem, of non-elastic material, having its ends curved back along said main stem once only, said curved parts having their ends bent toward the middle part of said main stem.
3. A compressible non-elastic space having

a main stem A, arch-shaped parts B B bent back from the ends of said main stem, said arch-shaped parts having one end movable along said main stem toward the middle thereof when the space is compressed, and resting on said main stem.

4. A compressible non-elastic space having

a main stem and having its ends bent back along said main stem once only at each end in the form of an arch.

D. BRAINERD RAY.
